US00D573123S

(12) **United States Design Patent**
Kim et al.

(10) **Patent No.:** US D573,123 S
(45) **Date of Patent:** ** Jul. 15, 2008

(54) **MOBILE PHONE**

(75) Inventors: **Young Se Kim**, Palo Alto, CA (US);
Young Ju Yeo, Seoul (KR); **Chang Hwan Hwang**, Kyunggi-do (KR)

(73) Assignee: **Samsung Electronics Co., Ltd.** (KR)

(**) Term: **14 Years**

(21) Appl. No.: **29/259,770**

(22) Filed: **May 15, 2006**

(51) **LOC (8) Cl.** 14-03

(52) **U.S. Cl.** D14/138

(58) **Field of Classification Search** D14/137,
D14/138, 147, 218, 341-347; 455/90.3,
455/556.1, 556.2, 575.1, 575.3, 575.4; 379/433.01-433.13;
361/814; 348/14.02

CLAIM

The ornamental design for mobile phone, as shown.

DESCRIPTION

FIG. 1 is a perspective view of the ornamental design of the present invention;

FIG. 2 is a front elevational view of the ornamental design of the present invention;

FIG. 3 is a rear elevational view of the ornamental design of the present invention;

FIG. 4 is a left side elevational view of the ornamental design of the present invention;

FIG. 5 is a right side elevational view of the ornamental design of the present invention;

FIG. 6 is a top plan view of the ornamental design of the present invention;

FIG. 7 is a bottom view of the ornamental design of the present invention;

FIG. 8 is a perspective view showing the mobile phone in an open position; and,

FIG. 9 is a perspective view showing the mobile phone in an open position with the middle screen in the rotated position.
